UNITED STATES PATENT OFFICE

VINCENT MENINNO, OF NASHUA, NEW HAMPSHIRE

SHOE HEEL BASE

Application filed March 7, 1929. Serial No. 345,059.

This invention relates to what are known as the heel bases of shoes.

In the present day manufacture of shoes, especially those equipped with rubber heels, it is customary to use what is known as a heel base between the wearing surface of the heel and the heel part of the outer and inner sole.

These bases have a substantially flat face at the bottom where the wearing part of the heel is attached and at the top face are made concave. The concavity is produced either by attaching around the outside edge of the top face at the back and sides, a rand, or by making a blank with parallel top and bottom faces and then gouging out the top to form a concavity of the desired depth and shape.

The first class heel bases are made of one section or lift of good real leather around the edge of the top face of which is cemented a rand also of first class real leather. As leather is expensive and there is considerable loss in cutting, while this makes the best base, it is expensive.

Heel lifts have been made by taking a large number of pieces all of substantially the same thickness and putting them together like a puzzle, then cementing over the entire top a thin piece of material, thus holding them together.

Heel bases have been made by taking a number of pieces of leather or other material of various shapes and sizes and imbedding in them a metal plate to hold the whole outfit together.

Other heel bases have been made by providing certain parts of uniform size and associating with them a third part which may be of variable sizes to make heel bases of different sizes and holding all together by a complete lift of some other material which shows at the edges.

Other heel bases have been made of leather board with the top gouged out or with some leather board used in connection with a leather rand, but leather board soaks up water like a sponge and is very objectionable in the finished shoe, although it is cheap.

The objection to various built up heel bases is that the operation of assembling

them is slow and therefore expensive, and in some of them there are too many breaks which show on the outside of the heel.

The purpose of this invention is to provide a heel base of the first quality made entirely of leather sections, such sections being of such character that they can be very quickly assembled and held together until a leather rand is attached, and so that when attached they are very firm and will not separate nor lose their shape in any respect.

I accomplish this by using two sections only, having adjoining straight edges and over the bottom face along the middle I cement a connecting strip of sheet material while, preferably, the rand is afterwards cemented around the outside of the top edge of the sections. Thereby the rand helps to hold the whole organization together especially if it is on one side and the patch on the other and when the base is assembled with a wearing heel, the patch is not only invisible but the whole organization is held together by the usual nails.

Another feature of my device is the use of nail hole segments whereby the middle nails can go through without having any tendency to separate the two heel sections.

My patch or strip which holds the two sections together during the assembling process is preferably very thin and tough and it is completely buried in the sections after the completed base has passed through the great pressure of the heel compression machine and the patch never appears on the edges.

Assembling with only two pieces in a heel machine can be done very rapidly because a pile of sections can be in reach of each hand and when two sections are brought together in a form or chute, the strip is instantly placed over the junction, pressure is applied and the operator is ready for another layer.

In the drawings, Fig. 1 is a vertical sectional elevation showing certain parts of a shoe with my base, and a wearing heel attached thereto.

Fig. 2 shows the two sections of a heel base of my preferred construction placed together before the connecting strip is cemented in position.

Fig. 3 shows this strip cemented in place. Fig. 4 is an elevation from the left of Fig. 3, and

Fig. 5 is an elevation from the right of Fig. 3.

Fig. 6 is an elevation from the bottom of Fig. 2, and

Fig. 7 is an elevation from the bottom of Fig. 3.

Fig. 8 is a perspective view showing the top face with a rand attached.

Fig. 9 is an elevation as from the right of Fig. 8, or what might be called the front of the base.

Fig. 10 is a plan view similar to Fig. 3 of a modification.

Fig. 11 is an elevation similar to Fig. 9 of a modification.

In the drawings, A is the upper, B the inner sole, and C the outer sole of a shoe.

F is my heel base, and G is the wearing surface which, as shown, is a rubber heel of the well-known type. This heel has nail holes indicated by 10 in which the heads of the nails H which fasten G and F to outer sole C are buried. Ordinarily there are about nine nails, the ones shown in Fig. 1 being the nails at the front and the back.

In my preferred type of heel base, I cut out of scrap leather, all of the same thickness, similar sections 30 and 31, each having a straight edge 32 or 33 and each having in corresponding positions the two half nail holes 34 and 36 and 35 and 37.

It makes no difference whether the straight edges of the two sections are put together each with the grain or flesh side up, or one with the grain and one with the flesh. The fronts 132 and 133 are shown as slightly curved, and the sides and back 134 and 135 are equally curved so that when put together the two sections are the shape of the heel desired.

I now use a connecting strip of thin material 42 which may be thin leather, cloth, parchment, fibre or any material with which to hold the sections together until they are assembled with the rand. To cement strip 42 over the middle of the adjoining face portions of the sections, I prefer to use some type of strong glue which will harden quickly and which will remain relatively hard so that the two sections can be readily handled without bending or cracking.

I then take a leather rand 45 of the usual form which tapers in height from the outside to the inside and curve it around the top outside edge of the two united sections, cementing it in position preferably with a cement or glue which is somewhat flexible.

The assembly is now held together by the strip 42 on the bottom face, and the rand on the top face.

Before attaching the rand, or during that process, or afterwards, I prefer to subject the sections 30 and 31 to great pressure where-

by the connecting strip 42 is practically imbedded in the sections 30 and 31, thus making the bottom face 130, as shown in Fig. 9, practically level and flat, while whatever slight distortion there may be of the top face 131 is immaterial because it is taken up by the curvature of the rand 45.

With the above construction, the only joint which shows is at 40 because the joint 41 at the front is entirely out of sight. The nails such as H, H when driven in pass through the nail holes 34, 35 and 36, 37 respectively and pass through strip 42 or not, according to its size. By providing these nail holes, the tendency of the nails to separate the two sections is avoided.

In Fig. 10, I show an assembly of two sections 50 and 51 which are not similar but which do have the corresponding straight edges 52 and 53 where they are put together. Over the middle of the adjoining face portions, I cement the connecting strip 54 of thin material and except that I use no nail holes, the layer formed by the two sections is the same as that shown in Figs. 2 and 3 and to its is attached a rand in a manner similar to what is shown in Figs. 1, 8 and 9.

In assembling this type of layer, it saves time to have a pile of sections 50 in reach of one hand and a pile of sections 51 in reach of the other hand.

As shown in Fig. 11, I may attach a strip 142 on the same face with rand 45 but in such case, there is a slight tendency for the bottom edges of the sections at 41 to separate.

I claim:

1. A heel base formed to be interposed between the outer face of the heel end portion of a shoe outsole and the top face of a heel attached to the sole, said heel base comprising a heel-shaped layer composed of two similarly shaped pieces, placed together at their respective straight edges, each piece having two half nail holes which adjoin those on the other piece thereby forming two holes along a middle line from front to back; a connecting strip of thin material cemented over the adjoining middle face portions of said sections; and a curved rand which tapers in height from the outside to the inside, said rand being cemented along the top outside edge of said two united sections.

2. In a shoe heel base, the combination in one layer of two similar sections placed together at their respective straight edges, each of said straight edges having half of a nail hole; with a connecting strip of thin sheet material cemented over the middle of the adjoining face portions of said sections; and a curved bevelled rand cemented around the top outer edges of said layer.

3. In a shoe heel base, the combination in one layer of two leather sections placed together at their respective edges; with a connecting strip of thin sheet material of less

size than the combined sections cemented over the middle of the adjoining bottom face portions of said sections and so positioned thereon and imbedded therein that its edges 5 are covered; and a curved beveled rand cemented around the outer edges of the top faces of said sections.
